United States Patent Office

Des. 206,523
Patented Dec. 27, 1966

206,523

SHELTER

James L. Artig, White Bear Lake, Minn., assignor to
Artig Products, Inc., a corporation of Minnesota

Filed June 11, 1965, Ser. No. 85,677

Term of patent 14 years

(Cl. D12—2)

FIG. 4

FIG. 5

FIG. 1

FIG. 2

FIG. 3

FIG. 6

FIG. 1 is a front elevational view of a shelter, showing my new design;

FIG. 2 is a view similar to FIG. 1 with the top member oriented 90° with respect to the bottom member;

FIG. 3 is a bottom plan view of FIG. 1;

FIG. 4 is a top plan view of FIG. 1;

FIG. 5 is a sectional view of the bottom along line 5—5 of FIG. 1; and

FIG. 6 is a sectional view of the bottom along line 6—6 of FIG. 3.

I claim:

The ornamental design for a shelter, as shown.
